UNITED STATES PATENT OFFICE

CHARLES ALGERNON PARSONS, OF NEWCASTLE-ON-TYNE, ENGLAND, AND ERNEST HENRY BUCHANAN ANDERSON, OF NEW YORK, N. Y.; SAID ANDERSON ASSIGNEE TO SAID PARSONS

ELASTIC FLUID TURBINE

Application filed October 12, 1927, Serial No. 225,727, and in Great Britain November 18, 1926.

The invention relates to elastic-fluid turbines or turbine units of the kind designed to operate efficiently over a considerable range of power, the object of the present invention being to provide an improved form of such a unit.

With such an object:—

The invention consists in an elastic-fluid turbine unit comprising the combination of elements hereinafter described and particularly pointed out in the claims.

The accompanying drawing shows in sectional elevation an illustrative structural embodiment of the invention.

In carrying the invention into effect according to this form, the cruising impulse blading, *a*, and cruising reaction blading, *b*, together with the main impulse blading, *c*, and main reaction blading, *d*, are carried on a single rotor, *A*, in the sequence set forth.

A regulating valve, *B*, is provided for admitting live steam direct to the nozzles of the cruising impulse stage while a main regulating valve, *C*, admits live steam to the nozzles of the main impulse stage. Further, a by-pass, *D*, connects the exhaust side of the cruising impulse blading, *a*, to the exhaust side of the main impulse blading, *c*, this by-pass being controlled by a suitable valve, *E*.

In addition, steam can by-pass the main impulse blading, *c*, through apertures, *f*, in the impulse wheel disc, *h*.

The turbine unit above described is operated as follows:—

At full power the cruising regulating valve, *B*, is closed and the main regulating valve, *C*, opened, steam thus passing through the main impulse and reaction blading, *c* and *d*, while the cruising impulse and reaction blading, *a* and *b*, rotates idly in steam at the pressure of the main impulse stage exhaust.

Preferably the by-pass valve, *E*, in these circumstances is opened so that the low-pressure steam may circulate freely through the cruising blading, *a*, *b*.

At intermediate powers the main regulating valve, *C*, is closed and the by-pass, *E*, and cruising regulating valves, *B*, opened.

Steam then passes through the cruising im-

pulse blading, *a*, through the by-pass, *D*, to the main reaction blading, *d*, thereby short-circuiting both the cruising reaction blading, *b*, and the main impulse blading, *c*. In this case the idle parts rotate in steam at the pressure of the cruising impulse stage exhaust.

Finally at cruising powers the by-pass, *E*, and main regulating valves, *C*, are closed and the cruising regulating valve, *B*, opened. Steam now passes through the cruising impulse and reaction blading, *a* and *b*, by-passes the main impulse blading, *c*, (for example, by the disc apertures, *f*), and continues through the main reaction blading *d*. Similarly in this case the idle stage, namely the main impulse blading, rotates in steam at a low pressure.

In the structural form of the invention above described it will be seen that there are no diaphragms or internal packings while the windage losses are in all cases small due to the fact that the idle parts are rotating in steam which has been expanded to a low pressure.

The detailed structural embodiment of the invention may take other forms than those described above.

Having now described our invention, what we claim as new and desire to secure by letters Patent is:—

1. An elastic-fluid turbine unit comprising in combination a rotor; a stator casing surrounding said rotor to provide a continuous annular passage available for flow of motive fluid and disposed in said passage in the sequence set forth, cruising impulse and reaction blading and main impulse and reaction blading; and means for by-passing motive fluid from a point of said passage between said cruising impulse and reaction blading to a point of said passage between said main impulse and reaction blading.

2. An elastic-fluid turbine unit comprising in combination a rotor; a stator casing surrounding said rotor to provide a continuous annular passage available for flow of motive fluid and disposed in said passage in the sequence set forth, cruising impulse and reaction blading and main impulse and re-

action blading; and means for by-passing motive fluid from said cruising reaction to said main reaction blading.

3. An elastic-fluid turbine unit comprising in combination a rotor; a stator casing surrounding said rotor to provide a continuous annular passage available for flow of motive fluid and disposed in said passage in the sequence set forth, cruising impulse and reaction blading and main impulse and reaction blading; and means mounted on said rotor and carrying said main impulse blading, said carrying means being perforated to permit motive fluid to by-pass from said cruising reaction to said main reaction blading.

4. An elastic-fluid turbine unit comprising in combination a rotor; a stator casing surrounding said rotor to provide a continuous annular passage available for flow of motive fluid and disposed in said passage in the sequence set forth, cruising impulse and reaction blading and main impulse and reaction blading; independent supplies of motive fluid to said cruising impulse and to said main impulse blading; and independent means for by-passing exhaust motive fluid to said main reaction blading from both said cruising impulse and said cruising reaction blading.

In testimony whereof we have signed our names to this specification.

CHARLES ALGERNON PARSONS.
ERNEST H. B. ANDERSON.
